UNITED STATES PATENT OFFICE

2,392,640

SAFETY RAZOR BLADE SHARPENER

Raymond G. Bryan, Kansas City, Kans.

Application May 12, 1945, Serial No. 593,428

8 Claims. (Cl. 51—218)

My invention relates to a device for holding safety razor blades while sharpening the same, and one object of the invention is to provide a device of this character whereby a blade may be held at an angle to ensure proper sharpening of the beveled cutting edges thereof while the blade is reciprocated upon the surface of a suitable sharpening agent such, for instance, as a hone, strop, or newspaper.

Another object of the invention is to provide a device of this character which is so shaped and proportioned as to present the beveled cutting edges of the blade to the sharpening surface at the proper angle to receive keen cutting edges, thereby acting as a guide in relieving the operator of the necessity of determining such angle when sharpening the blade.

A further object of the invention is to provide a device of this character which is simple in construction, inexpensive to manufacture and is very efficient for the purpose intended.

In order that the invention may be fully understood, reference will now be had to the accompanying drawing, in which:

Fig. 1 is a perspective view of the two members constituting the device.

Fig. 2 is an end view showing a double edged razor blade interposed between two members constituting the device.

Fig. 3 shows the device in position for sharpening one edge of the blade.

Fig. 4 shows the device in position for sharpening the other edge of the blade.

Figs. 5 and 6 are plan views.

In carrying out the invention I provide a one-piece member 2 comprising a handle 4 and a base 6, which latter is of inverted triangular cross section. The under portion of base 6 has two equal sides 8 and 10, respectively, which diverge equally from the apex 12 of the triangle to the longitudinal margins of the upper flat surface 14 of the base, which latter provides a support for a double edged razor blade A. The base 6 is of less width than the blade A, and the angle at which the sides 8 and 10 extend from the apex 12 is such that when base 6 is tilted to the positions shown by Figs. 3 and 4 the beveled portions B and C, respectively, of the blade will be carried into flat contact with the sharpening surface D.

The handle 4 is preferably of the same length as base 6, from the upper central portion of which it extends and is adapted to pass through the usual longitudinal slot in the blade and prevent the same from shifting laterally or longitudinally upon the base 6.

The other member of the device consists of a guard plate 16 having a centrally-disposed longitudinal slot 18 to permit it to be lowered over the handle 4 and rest on top of the blade A. The guard plate 16 overlaps the sharp edges of the blade and thus protects the fingers of the operator from being cut when the device is being used. The guard plate 16 is bent upward at oblique angles intermediate its longitudinal margins 20 to prevent the latter from coming into contact with the sharpening surface D, when the device is tilted to the positions disclosed by Figs. 3 and 4, respectively.

In practice, when the beveled edges are to be sharpened the blade A is placed in position upon the upper surface 14 of the base 6, after which the guard plate 16 is lowered over the handle 4 until it rests upon the blade. The handle 4 is then grasped with the fingers and the device may be tilted first to the position shown by Fig. 3 to carry the side 8 of the base 6 and the beveled edge B of the blade into contact with the sharpening surface D preparatory to moving the blade back and forth over said sharpening surface. During the sharpening operation the guard plate 16 is held down upon the blade with the fingers and sufficient pressure is applied to insure proper sharpening of the blade.

After the beveled edge B has been sharpened the device is tilted to the position shown by Fig. 4 to bring the side 10 of base 6 and the beveled edge C of the blade into sharpening position upon the surface D. After the beveled sides B and C have been sharpened, the blade A is removed from the device and then replaced upon the base 6 in a reverse position preparatory to sharpening the beveled edges E and F of the blade.

During the sharpening of the left edge of the blade the device may be held at an angle to the forward movement indicated by the arrow Fig. 5, and when the right edge is being sharpened the device may be held at an angle to the forward movement indicated by the arrow Fig. 6. However, the device may be held in other positions during the sharpening operation. When the device is moved in a reverse direction to that indicated by the arrows, the device may be tilted or raised from the sharpening surface D to prevent the blade from cutting into said surface.

Although the guard plate 16 is desirable as a protection against cutting the fingers during the sharpening operation, it may be dispensed with as the blade may be held down upon the base member 6 with the fingers when grasping the

handle 4 without danger of cutting the fingers if the operator exercises due care.

From the foregoing description it is apparent that I have provided a device which is well adapted for the purpose intended, and while I have shown the preferred form of such device I reserve all rights to such other forms and modifications thereof as properly fall within the spirit and scope of the invention as claimed.

Having thus described my invention, what I claim and desire to secure by Letters Patent, is:

1. A safety razor blade holder comprising first and second members adapted to hold a safety razor blade therebetween while the blade is being sharpened, the first member comprising a base of inverted triangular cross section and a handle projecting upwardly from said base and adapted to pass through the usual slot in the blade to position the same upon the base, said second member comprising a plate having a slot so that it may be lowered over the handle and be pressed down upon the blade to hold the same upon the base during the sharpening operation.

2. A safety razor blade holder comprising first and second members adapted to hold a safety razor blade therebetween while the blade is being sharpened, the first member comprising a base of inverted triangular cross section of less width than the razor blade, and a handle projecting upwardly from said base and adapted to pass through the usual slot in the blade to position the same upon the base, said second member comprising a guard plate having a slot so that it may be lowered over the handle and be pressed down upon the blade to hold the same upon the base during the sharpening operation.

3. A safety razor blade holder comprising first and second members adapted to hold a safety razor blade therebetween while the blade is being sharpened, the first member comprising a base of inverted triangular cross section and a handle projecting upwardly from said base and adapted to pass through the usual slot in the blade to position the same upon the base, said handle being so proportioned as to prevent either lateral or longitudinal movement of the blade upon the base, said second member comprising a guard having a slot so that it may be lowered over the handle and be pressed down upon the blade to hold the same upon the base during the sharpening operation.

4. A safety razor blade holder comprising first and second members adapted to hold a safety razor blade therebetween while the blade is being sharpened, the first member comprising a base of inverted triangular cross section and a handle projecting upwardly from the longitudinal axis of said base and adapted to pass through the usual slot in the blade to position the same upon the base, said second member comprising a guard plate having a slot so that it may be lowered over the handle and be pressed down upon the blade to hold the same upon the base during the sharpening operation.

5. A safety razor blade holder comprising first and second members adapted to hold a safety razor blade therebetween while the blade is being sharpened, the first member comprising a base of inverted triangular cross section and a handle projecting upwardly from said base and adapted

to pass through the usual slot in the blade to position the same upon the base, said second member comprising a guard plate having a slot so that it may be lowered over the handle and be pressed down upon the blade to hold the same upon the base during the sharpening operation, said guard plate being so proportioned as to overlap the cutting edges of the blade.

6. A safety razor blade holder comprising first and second members adapted to hold a safety razor blade therebetween while the blade is being sharpened, the first member comprising a base of inverted triangular cross section and a handle projecting upwardly from said base and adapted to pass through the usual slot in the blade to position the same upon the base, said second member comprising a guard plate having a central longitudinal slot so that it may be lowered over the handle and be pressed down upon the blade to hold the same upon the base during the sharpening operation, said guard plate being turned upward at oblique angles intermediate its longitudinal margins to prevent the latter from contacting the surface on which the blade is sharpened.

7. A device for holding a double-edged safety razor blade while being sharpened comprising a base of inverted triangular cross section of less width than the blade and adapted to support the latter, the undersides of said base diverging upward from the apex of the angle at such degrees that when the base is tilted to bring either side flat upon the sharpening surface it will constitute a guide for proper placement of the adjacent cutting edge of the blade upon said surface, and a handle tapered upward from the central longitudinal axis of the top of the base whereby the latter may be tilted, said handle being adapted to pass through the usual longitudinal slot in the blade to permit the latter to rest upon the base, the lower portion of the handle being so proportioned as to prevent lateral or longitudinal shifting of the blade upon the base.

8. A device for holding a double-edged safety razor blade having a central longitudinal slot, comprising a one-piece member consisting of a base and a handle, said base being of triangular cross section of less width than the blade and provided with a flat upper surface for the blade to rest upon, the undersides of said base diverging upward from the apex of the angle to such degree that when the base is tilted to bring either side flat upon a sharpening surface it will place the adjacent cutting edge of the blade in proper sharpening position, said handle being of substantially oblong configuration and approximately the same length as the base from the intermediate upper surface of which it tapers to pass through the slot in the blade so that the latter may rest upon the base, the lower portion of the handle being proportioned to fit snugly in the slot to hold the blade from shifting upon the base, and a guard plate having a central longitudinal slot so that it may pass over the handle and be pressed down by the fingers against the blade during the sharpening operation, said guard plate having a flat intermediate portion with upturned longitudinal sides to avoid contact with the sharpening surface.

RAYMOND G. BRYAN.
